UNITED STATES PATENT OFFICE.

CHAUNCEY DE VOE, OF NEW YORK, N. Y.

SASH-FASTENER.

1,253,474.

Specification of Letters Patent. Patented Jan. 15, 1918.

Application filed June 5, 1917. Serial No. 172,955.

To all whom it may concern:

Be it known that I, CHAUNCEY DE VOE, a citizen of the United States, and a resident of the city of New York, in the county of Bronx and State of New York, have invented certain new and useful Improvements in Sash-Fasteners, of which the following is a specification.

The present invention relates to improvements in window sash fasteners, and more particularly to that type which is secured to the upper rail of the lower sash of the window and is adapted to bear or bind against some portion, for instance one of the 15 stiles, of the upper sash.

One of the objects of the invention is to provide an improved and simple form of sash fastener which will lock the two sashes together at any desired relative position, so 20 that the window may be left open a sufficient distance for ventilation either on the top or at the bottom, or at both, and prevent the lower sash from being pushed farther upward or the top one from being pulled down 25 to a sufficient extent to enable a person to gain access to the room or house through the window.

Another object of the invention is to produce a sash lock having means which prevents the "picking" of the lock by means 30 of a blade or similar contrivance.

A further object of the invention is to provide a sash fastener which can be manufactured on a commercial scale, or in other 35 words one which is not so difficult to produce as to be beyond the reasonable cost of such an article.

With these and other objects in view, which will more fully appear as the nature 40 of the invention is better understood, the same consists in the combination, arrangement, and construction of parts hereinafter described, pointed out in the appended claims and illustrated in the accompanying 45 drawings, it being understood that many changes may be made in the size and proportion of the several parts and details of construction within the scope of the appended claims without departing from the spirit 50 or sacrificing any of the advantages of the invention.

One of the many possible embodiments 55 of the invention is illustrated in the accompanying drawings, in which:—

Figure 1 is a side elevation, partly in sec-

tion, of the improved fastener, the same being shown in suitable position relative to the upper and lower sashes of a window, and the latter being shown in section; Fig. 2 is a section taken on line 2—2 of Fig. 1, certain 60 parts being removed to more clearly show the construction; Fig. 3 is a front elevation of the device shown in Fig. 1; and Fig. 4 is a view similar to the one shown in Fig. 1, with the sash fastener in its inoperative po- 65

In the drawings, the upper sash of the window is represented at 10, and the lower sash at 11. To the top of the upper rail of the lower sash is secured by screws, or otherwise, the base plate 12 of the fastener. With this base plate may be made integral or there may be attached thereto, in any suitable manner, two parallel upwardly projecting frame portions 13, in which is rotatably 70 mounted a spindle 14. To this spindle is rigidly secured a locking piece or lever 15, having a cam-shaped surface 16, which is adapted to come into contact with a channel iron 17 upon the inner surface of the upper 75 sash, for instance upon one of its stiles, when said lever is in its operative position (Fig. 1). The eccentricity of the cam-shaped face of the locking lever increases gradually from the lowermost edge 18 of the lever to its up- 80 permost edge 19, so as to take a firm grip 85 on the channel iron 17 when brought into contact therewith, and to effectively prevent relative motion of the two sashes.

The lever 15 is provided in front of the 90 spindle 14 with an arc-shaped portion 20, having ratchet teeth 21, which are adapted to be engaged by a somewhat resilient pawl 22. This pawl is made in the form of a plate, having a width corresponding to that 95 of the cam-shaped face 16 of the lever 15. The pawl is pivoted at 23 to the upwardly projecting frame portions 13, and is disposed below the locking piece or lever 15. The front portion of the pawl is bent up- 100 ward, as clearly shown at 24, its free end being adapted to engage with the ratchet teeth 21 and provided with a finger piece 25, for a purpose hereinafter to be described. The outer free end 26 of the pawl projects be- 105 yond the outer face of the lower sash 11 into the channel iron 17. A spring 27 causes the upwardly extending portion 24 of the pawl to contact with the lever 15.

With the locking lever 15 is made integral, 110

or there may be attached thereto, a downwardly projecting lug or extension 28, that is adapted to bear against the pawl 22.

The operation of this device is as follows:

- 5 When the locking lever 15 is forced into contact with the channel iron 17, its cam-shaped face 16 engages with and binds against the said channel iron. As the locking lever is being shifted from its inoperative position (Fig. 4) to its operative position (Fig. 1), the lug 28 causes the pawl to swing around its pivot 23, and its outer free end 26 to come into contact with the channel iron 17, thereby closing the gap between 10 the two sashes. At the same time the upwardly extending portion 24 of the pawl engages one of the ratchet teeth 21, depending upon the position of the locking lever. If it is attempted to raise the lower sash, obviously the friction between the cam-shaped face of the locking lever and the channel iron will cause rotation of the locking lever in the direction of the arrow shown in Fig. 1 of the drawings, and will consequently 15 force the said locking lever against the angle iron and bind the two sashes together in direct proportion to the upward pressure, owing to the eccentricity of said lever. On the other hand, should it be attempted to lower the upper sash, such movement will be prevented by the pawl 22, in engagement with one of the ratchet teeth 21.

Inasmuch as the pawl abuts against the channel iron, when the locking lever is in its operative position (Fig. 1), the insertion of a blade-like instrument will be effectively prevented thereby, so that a picking of the lock becomes impossible.

The channel iron 17 has a two-fold purpose, towit: First, it presents a proper surface for contact with the locking lever, and, second, it prevents a sharp-pointed instrument from being driven through the stile of the window sash for picking the lock in this manner.

Copies of this patent may be obtained for five cents each, by addressing the "Commissioner of Patents, Washington, D. C."

When it is desired to release the lock, the pawl 22 is disengaged from the ratchet teeth on the locking lever, by taking hold of said pawl by the aid of the finger piece 25 and forcing it downward against the action of the spring 27. The locking lever can then be swung into the position shown in Fig. 4 of the drawings, thus allowing free movement of both sashes in both directions.

What I claim is:

1. The combination with the upper and lower sashes of a window, of a frame mounted upon said lower sash, a locking lever fulcrumed to said frame having a cam-shaped contacting surface adapted to bear against said upper sash, a plate member pivoted to said frame below said locking lever having one of its ends projecting toward said upper sash, and an extension upon said lever for causing said plate member to swing around its pivot and to close the gap between said two sashes when said lever is shifted to its operative position.

2. The combination with the upper and lower sashes of a window, of a frame mounted upon said lower sash, a locking lever fulcrumed to said frame having a cam-shaped contacting surface adapted to bear against said upper sash, said lever being provided with an arc-shaped portion having ratchet teeth, a spring-pressed pawl pivoted to said frame below said locking lever having one of its ends projecting toward said upper sash and its other end formed to engage said ratchet teeth, and an extension upon said lever for causing said pawl to swing around its pivot when said lever is shifted to its operative position, thereby projecting over the gap between said sashes and also engaging with said ratchet teeth.

Signed at New York, in the county of New York and State of New York, this 1st day of June, A. D. 1917.

CHAUNCEY DE VOE.
